United States Patent Office

Des. 228,322
Patented Sept. 11, 1973

228,322

BRASSIERE

Sam Guberman, Bayonne, N.J., assignor to Maidenform, Inc., New York, N.Y.

Filed Nov. 16, 1971, Ser. No. 199,403

Term of patent 14 years

Int. Cl. D2—01

U.S. Cl. D2—24

The figure is a front perspective view of a brassiere showing my new design, the back of the brassiere being conventional.

I claim:

The ornamental design for a brassiere, substantially as shown and described.
